UNITED STATES PATENT OFFICE.

GEORGE SCHLEUSSELBURG, OF DETROIT, MICHIGAN, ASSIGNOR TO HIMSELF, ROBERT F. HARTENSTEIN, AND J. CHAS. EICHHORN, TRUSTEES.

ALCOHOL-GAS STOVE.

1,266,863.

Specification of Letters Patent. Patented May 21, 1918.

Application filed April 12, 1917. Serial No. 161,544.

To all whom it may concern:

Be it known that I, GEORGE SCHLEUSSELBURG, a subject of the Emperor of Germany, residing at Detroit, in the county of Wayne 5 and State of Michigan, have invented certain new and useful Improvements in Alcohol-Gas Stoves, of which the following is a specification, reference being had therein to the accompanying drawings.

10 This invention relates to a vapor generator and has special reference to a device for generating vapor that may be used for heating and illuminating purposes, particularly in residences and small compartments.

15 The primary object of my invention is to provide a gas generating device in which alcohol can be easily and quickly vaporized, atomized, or converted into vapor that may be safely used for heating and illuminating 20 purposes, and provision is made for utilizing any condensate of alcohol in connection with the device or about a stove or a heating apparatus, so as to avoid waste and reduce operating expenses to a minimum.

25 Another object of my invention is to provide a generating device in which alcohol or kerosene or gasoline can be easily and quickly converted into a vapor to be used as fuel for a stove or for illuminating purposes, and in either instance the vapor is of 30 such nature as to preclude asphyxiation or explosion should the vapor escape into a room or compartment.

35 A further object of my invention is to provide a vapor generating device wherein the parts are constructed and assembled with a view of reducing the cost of manufacture and at the same time retain those features by which safety, durability, ease of 40 regulating and a high degree of efficiency are secured. With such ends in view, my invention resides in the novel construction to be hereinafter described and then claimed.

45 Reference will now be had to the drawings, wherein—

Figure 1 is a front elevation of the vapor generating device associated with a stove and illumination vapor burners;

Fig. 2 is a vertical sectional view of the 50 generating device; and

Fig. 3 is a detail sectional view of a needle or regulating valve adapted to form part of the device.

In describing my invention by aid of the

views above referred to, I desire to point 55 out that the same are merely illustrative of the vapor generating device as now constructed and in use, and I do not care to confine myself to the precise construction and arrangement of parts shown. The following description is therefore to be broadly construed as including such substitute construction and arrangement of parts which are the obvious equivalent of those to be hereinafter referred to. 60

In the drawings, 1 denotes a base provided with a cylindrical housing 2 which has the top thereof formed with a central opening 3. In the housing 2 is an alcohol burner, constituting a source of heat, and as shown 70 the burner is in the form of a large lamp having a receptacle 4 provided with a detachable cap 5 so that the receptacle may be filled with alcohol or other fuel. The receptacle 4 has a burner 6 provided with a 75 wick 7 preferably of the cylindrical type, that may be adjusted by the usual wick feeding mechanism, generally designated 8 and operable from the outer side of the housing 2. 80

Fitted in the opening 3 of the housing 2 is a lower casing 9 and mounted on the lower casing 9 is an upper casing 10. Supported within the lower casing 9 or resting on the burner of the receptacle 4 is a main 85 tank 11 provided with a vapor inlet connection 12 and a vapor outlet pipe 13, the latter extending out of the lower casing 9. The main tank 11 is formed with a central vertically disposed flue 14 with the lower 90 part of the flue conical shape to provide clearance for the burner 6 and concentrate the flame thereof centrally of the tank 11 and around the vertical axis of the lower and upper casings 9 and 10. The central 95 flue 14 cooperates with walls of the tank 11 in providing an annular chamber 15 and this chamber is adapted to contain alcohol which may be vaporized by the heated walls of the flue 14. 100

Mounted in the upper end of the upper casing 10 is a feed tank 16 surrounded by a protecting shell 17. The feed tank 16 provides a peripheral chamber 18 and a central passage 19. Extending into the upper 105 end of the central passage 19 is a gas tank 20 having a peripheral chamber 21 and a central passage 22.

The bottom of the feed tank 16 has a depending well portion 23 and communicating therewith are the lower convolutions of coiled tubing 24 and 25, the former being arranged within the latter and extending into the central passage. The upper convolution of the coil of tubing 24 is connected to the bottom of the vapor tank 20, and the top of this gas tank is connected by a pipe 26 to the connection 12 of the main tank 11, said pipe extending through the central passage 22 of the vapor tank 20 and downwardly through the inner coil of tubing 24. The upper convolution of the outer coil 15 of tubing 25 is connected to the bottom of the vapor tank 20 and extending into the top of the vapor tank 20 is an inverted U-shape siphon pipe 27, said pipe extending into the chamber 18 of the feed tank 16, so as to remove any liquid, alcohol or condensate from the vapor tank to the feed tank.

The top of the feed tank 16 is provided with a detachable cap 28 so that alcohol or other fuel may be placed therein, and the side of said feed tank has a conventional form of gage or sight glass 29 which permits of the level of alcohol within the feed tank being easily ascertained.

At the top of the vapor tank 20 is a conventional form of safety valve 30 which permits of an excessive pressure within the tank 20 opening the valve to allow excess vapor to escape, and such vapor enters a frusto-conical shape chimney 31 fitted over the upper end of the shell 17. The safety valve 30 is simply used as a safety factor in connection with the generating device, and the casings 9 and 10 are principally employed for confining the heat from the burner 6 around the inner and outer coils 24 and 25 respectively, while the chimney 31 finishes off the top of the device.

The bottom of the feed tank 16 is connected by a down pipe 32 to a regulating valve 33 in communication with the main tank 11. This regulating valve, as best shown in Fig. 3, may be in the form of a needle valve having a needle 34 that can be adjusted to regulate the passage of alcohol from the feed tank 16 to the main tank 11. It is possible to set the needle 34 of the regulating valve 33 to admit a predetermined quantity of alcohol to the main tank 11, so as to maintain a predescribed level of alcohol therein.

As illustrating the use of the vapor generating device there is shown in Fig. 1, a vapor burning stove or cooking range 35 having the usual vapor burner supplied by a horizontally disposed pipe 36 connected to the pipe 13. The horizontally disposed burner pipe 36 has suitable connections 37 with a drain pipe 38 that extends into the housing 2 and is connected to the fuel

burner, said drain pipe conducting any condensate in the pipe 36 back into the receptacle 4 of the burner.

The pipe 36 may also be connected to a suitable pipe 39 for supplying burners 40 for illuminating purposes.

With the wick 7 adjusted and quantities of alcohol in the receptacle 4, the main tank 11 and the feed tank 16 the wick 7 can be lighted by opening a door 41 of the casing 9. The flame of the lamp or burner will impinge against the wall of the flue 14, the coils 24 and 25, and the walls of the central passages 19 and 22 of the tanks 16 and 20 respectively. The alcohol within the chamber 15 of the main tank 11 will be heated and vaporized to a certain extent but the greatest vaporization of alcohol takes place in the coils 24 and 25. The vaporized alcohol from these coils passes into the chamber 21 and from said chamber through the pipe 26 to the main tank 11, this tank supplying the stove 35 and the burners 40 through the medium of the pipes 13, 36, and 39. The alcohol within the chamber 18 of the feed tank 16 will feed by gravity through the pipe 32 to the needle valve 33, and with the needle 34 of said valve properly adjusted, a desired level of alcohol may be maintained within the chamber 15 of the main tank 11, so that there will always be sufficient space within the chamber 15 to receive vapor from the pipe 26 in order that it may reach the pipe 13.

Before there will be an excessive pressure of vapor within the chamber 21 of the vapor tank 20, the pipe 27 will admit a quantity of vapor to the chamber 18 of the feed tank 16, and should the lamp or burner be turned very low and a condensate or quantity of alcohol accumulate in the bottom of the chamber 21, this accumulated alcohol will be siphoned to the chamber 18 of the feed tank 16.

What I claim is:—

1. In a vapor generator, a burner, a main tank surrounding said burner adapted to contain fuel to be vaporized by heat from the said burner, said main tank having a vapor outlet, a feed tank adapted to contain fuel, coils subjected to the heat of said burner in communication with said feed tank to vaporize fuel received from said tank, and means for conducting vaporized fuel from said coils to said main tank.

2. In a vapor generator, a burner, a main tank adapted to contain fuel to be vaporized by heat from said burner, said main tank having a vapor outlet, a feed tank adapted to contain fuel, coils subjected to the heat of said burner and in communication with said feed tank to vaporize fuel received from said tank, means for conducting vaporized fuel from said feed tank to said main tank, and means adapted to regulate the

flow of fuel from said feed tank to said main tank.

3. In a vapor generator, a burner, a main tank adapted to contain fuel to be vaporized by heat from said burner, said main tank having a vapor outlet, a feed tank adapted to contain fuel, a gas tank, coils subjected to the heat of said burner and in communication with said feed tank to vaporize fuel received from said tank and conduct vaporized fuel to said vapor tank, and means for conducting vaporized fuel from said vapor tank to said main tank.

4. In a vapor generator, a burner, a main tank adapted to contain fuel to be vaporized by heat from said burner, said main tank having a vapor outlet, a feed tank adapted to contain fuel, coils subjected to the heat of said burner and adapted to receive fuel from said feed tank, a vapor tank adapted to receive vaporized fuel from said coils and supply the vaporized fuel to said main tank, means adapted for conducting fuel from said feed tank to said main tank, and means for regulating the flow of fuel from said feed tank to said main tank.

5. In a vapor generator, a feed tank adapted to contain fuel, coils in communication with said feed tank adapted for vaporizing the fuel, means for heating said coils, a vapor tank adapted to receive vaporized fuel from said coils, said gas tank having a gas outlet, and means establishing communication between said vapor and feed tanks adapted for conducting condensate within said vapor tank to said feed tank.

6. In a vapor generator, a source of heat, a main tank adapted to contain fuel to be vaporized by the source of heat, said main tank having a vapor outlet, a feed tank above said main tank and in communication therewith and adapted to contain fuel, means for regulating the communication between said feed tank and said main tank, a coil in communication with said feed tank adapted to receive fuel therefrom, said coil being subjected to the action of said source of heat so as to have the fuel therein vaporized, and means for conducting vaporized fuel from said coil to said main tank.

7. In a vapor generator, a fuel burner, a main tank adapted to contain fuel to be vaporized by the action of said fuel burner, a gas outlet pipe for said main tank, means for conducting condensate from said vapor outlet pipe to said fuel burner, a feed tank adapted to contain fuel and supply fuel to said main tank, a coil in communication with said feed tank subjected to the action of said fuel burner, and adapted to vaporize fuel, and means for conducting vaporized fuel from said coil to said main tank.

8. In a vapor generator, a fuel burner, a main tank adapted to contain fuel and subject it to the action of said fuel burner, a vapor outlet pipe connected to said main tank, means for conducting condensate from said vapor outlet pipe to said fuel burner, a feed tank adapted to contain fuel and supply the main tank with fuel, coils in communication with said feed tank adapted to receive fuel therefrom, said coils being subjected to the action of said fuel burner to vaporize the fuel in said coils, a vapor tank adapted to receive vaporized fuel from said coils, and means for conducting the vaporized fuel from said vapor tank to said main tank.

9. The combination with a vapor burning stove having a gas supply pipe, of a fuel burner, a main tank surrounding said fuel burner adapted to contain fuel and subject it to the action of said fuel burner to vaporize the fuel therein, a pipe connecting said main tank to the vapor supply pipe of said stove, a pipe connecting the vapor supply pipe of said stove to said fuel burner for conducting condensate from said gas supply pipe to said fuel burner, a supply of fuel above said main tank, and coils adapted to receive fuel from the supply thereof and be subjected to the action of said fuel burner to vaporize the fuel and supply said main tank with vapor.

In testimony whereof I affix my signature in the presence of two witnesses.
